UNITED STATES PATENT OFFICE.

RICHARD MARLOW, OF RALPH, ALABAMA.

PLOW.

1,418,156.

Specification of Letters Patent. Patented May 30, 1922.

Application filed September 25, 1920. Serial No. 412,718.

To all whom it may concern:

Be it known that I, RICHARD MARLOW, a citizen of the United States, residing at Ralph, in the county of Tuscaloosa and State 5 of Alabama, have invented certain new and useful Improvements in Plows; and I do hereby declare the following to be a full, clear, and exact description of the invention, such as will enable others skilled in the art 10 to which it appertains to make and use the same.

The present invention relates to plows, and aims to provide a plow comprising a novel assemblage of the component parts 15 and a simple construction, whereby the plow can be inexpensively manufactured, and in order that same will be thoroughly efficient and practical in use.

Another object is the provision of a plow 20 having a point piece which can be adjusted to take up wear and which can also be reversed to increase the life and utility thereof.

A further object is the provision of wings or shares which can be reversed to use both 25 the forward and rear edges thereof and thereby increase the life and utility of such wings or blades.

With the foregoing and other objects in view, which will be apparent as the description 30 proceeds, the invention resides in the construction and arrangement of parts hereinafter described and claimed, it being understood that changes can be made within the scope of what is claimed, without departing from the spirit of the invention.

The invention is illustrated in the accompanying drawing, wherein:

Figure 1 is a plan view of the improved plow.

Fig. 2 is a bottom view thereof.

Fig. 3 is a vertical section on the line 3—3 of Fig. 1.

The plow comprises a frog 6 which can be secured on the stock or standard of any 45 suitable plow beam, and which, as shown, has a downwardly extending lug 7 at its rear end to enter a slot 8 in the stock or standard 9, and a bolt 10 engages through the frog to extend through the slot 8 for clamping 50 the frog on said stock or standard.

A point piece 11 bears on the frog, longitudinally thereof, and its sides are arranged at an angle with one another, the same as the side portions of the frog 6, whereby the

piece 11 fits over the ridge of the frog, and 55 said piece has each end pointed, as at 12. A bolt 13 or similar clamping element engages through the piece 11 midway between the ends thereof, and extends downwardly through a longitudinal slot 14 in the ridge 60 of the frog 6, whereby to clamp the piece 11 on the frog, and enable said piece to be adjusted longitudinally. Thus, as the forward end 12 of the piece 11 is worn away, it can be resharpened, and the piece 11 ad- 65 justed forwardly to take up for the wear. Furthermore, by loosening the bolt 13, the piece 11 can be reversed end for end, to bring the other end thereof forward, and thus double the life of the "point" of the plow. 70

The frog 6 is provided adjacent to its forward end with extensions 15 extending toward opposite sides and rearwardly at acute angles with the body of the frog, and diverging rearwardly, and said extensions 75 are for the attachment of the wings or shares 16 which extend in the same directions as said extensions. The wings or blades 16 have the shape of a parallelogram and are reversible end for end. The adjacent end portions of the wings 16 overlap the extensions 15, and the adjacent ends of said wings abut the longitudinal edges of the piece 11. The wings 16 are provided at each end near the obtuse angled corners with 85 bolt holes or apertures 17 for the reception of bolts 18 which extend through the extensions 15, for clamping said wings on said extensions. By removing the bolts 18, the wings 16 can be reversed end for end, where- 90 by to bring the other ends thereof adjacent to the piece 11, thereby bringing the rear edges of the wings forward. Thus, both of the longitudinal edges of the wings can be sharpened, to double the life of said wings 95 by reversing them when the forward edges thereof become worn beyond further use. The point piece 11 is adjustable between the adjacent ends of the wings 16 when the bolt 13 is loosened and the side edges of the piece 11 in abutting the adjacent ends of the wings 16 will retain said piece in proper position flush with said wings, and the bolts 13 and 18 being flush with the piece 11 and wings 16, respectively, will leave the upper 100 surfaces thereof unobstructed, so as to avoid the accumulation of trash on the plow. 105

The wings 16 can be of different sizes

according to the "sweep" desired, and in some cases, the wing at one side can be shorter than the other or omitted.

Having thus described the invention, what is claimed as new is:—

A plow comprising a frog having extensions near its forward end extending toward the opposite sides, said frog having a ridge between said extensions, a point piece bearing on the frog over said ridge, said point piece having its opposite ends pointed and being adapted to be reversed end for end, a clamping bolt extending through said point piece midway between the ends thereof for clamping said piece on the frog, the frog having a longitudinal slot at said ridge receiving said bolt, a pair of wings each in the shape of a parallelogram having adjacent

ends overlapping said extensions, and bolts for removably clamping the end portions of 20 said wings on said extensions, said wings having apertures near their opposite ends for the engagement of the last named bolts and the wings being reversible end for end for attachment on said extensions, the adjacent ends of the wings abutting the side edges of said point piece with said point piece and wings flush with one another.

In testimony whereof I have signed my name to this specification in the presence of 30 two subscribing witnesses.

RICHARD MARLOW.
